(57) CLAIM

We claim the ornamental design for a grip for a sports pole, as shown and described.

DESCRIPTION

FIG. 1 is a side view of a grip for a sports pole; and, FIG. 2 is a side perspective view of the grip for a sports pole of FIG. 1.

The ornamental design that is claimed is shown in solid lines in the drawings. All surfaces not shown form no part of the claimed design.

1 Claim, 2 Drawing Sheets

FIG. 1

FIG. 2
